United States Patent Office.

C. A. GALE, OF DEMOPOLIS, ALABAMA.

Letters Patent No. 97,900, dated December 14, 1869.

IMPROVEMENT IN BLOTTING-PADS.

The Schedule referred to in these Letters Patent and making part of the same.

To all whom it may concern:

Be it known that I, C. A. GALE, of Demopolis, in the county of Marengo, and State of Alabama, have invented a new and improved Rolling Blotter; and I do hereby declare that the following is a full, clear, and exact description thereof, which will enable others skilled in the art to make and use the same, reference being had to the accompanying drawing, forming part of this specification.

Figure 1 is a top view of my improved rolling blotter.

Figure 2 is an end view of the same.

Figure 3 is a detail cross-section of the cylinder, taken through the line $x x$ fig. 1.

Similar letters of reference indicate corresponding parts.

My invention has for its object to furnish an improved rolling blotter, which shall be so constructed and arranged that the blotting-pads may be conveniently removed when required, and replaced with new ones; and

It consists in the construction and combination of the various parts of the blotter, as hereinafter more fully described.

A is the hollow cylinder, which may be made of any suitable material, and which is made in two parts hinged to each other at one side of the cylinder, as shown in figs. 2 and 3.

The parts of the cylinder A, when closed, are secured in place by the catches or latches B, pivoted to the ends of one part of the cylinder A; and catching upon pins or catches C attached to the other part of said cylinder.

Several notches are formed upon the latches B, so that they may catch upon the said pins C, and hold securely, whatever be the thickness of the blotting-pad placed upon the cylinder.

The forward ends of the latches B are bevelled off, and they are held down by springs D, so that they may catch upon the pins C automatically, when the parts of the cylinder are forced together.

The latches B are held up against the ends of the cylinder A, by straps, as shown in fig. 2.

To the middle points of the ends of the cylinder A,

are attached pivots which enter and revolve in holes in the ends of the arms of the branched handle E.

F is the blotting-pad, one end of which is inserted in the space between the bar a' , and the inner surface of one edge of one of the parts of the cylinder A.

The pad F is then passed around the outer surface of the cylinder A, and its other end is bent in over the edge of the other part of said cylinder, which edge may be serrated to enable it to take a firmer hold upon the blotting-pad.

The cylinder is then closed, clamping the ends of the blotting-pad between the edges of the said cylinder, and holding the said pad securely drawn around the outer surface of the cylinder A.

By this construction, when the blotting-pad F has become soiled from use, it may be easily detached and replaced by a new one.

G is a spring, one end of which is attached to one of the parts of the cylinder A, near its hinged edge, and the other end of which rests against the inner surface of the other part of said cylinder near its hinged edge, so that when the spring-fastenings B C D are unfastened, the spring G may force the parts of the cylinder apart, allowing the blotting-pad F to be conveniently detached.

Having thus described my invention, I claim as new, and desire to secure by Letters Patent—

1. Forming the cylinder A, to which the blotting-pad is attached, in two segments hinged to each other at one edge, and secured to each other when closed by the spring-latches B C D, or equivalent fastenings, substantially as herein shown and described, and for the purpose set forth.

2. The spring-fastenings B C D, constructed and operating substantially as herein shown and described, in combination with the hinged parts of the cylinder A, as and for the purpose set forth.

The above specification of my invention signed by me, this 30th day of August, 1869.

C. A. GALE.
